Primary Examiner — Lauren D McVey

(57) **CLAIM**

The ornamental design for a monitor support arm, as shown and described.

DESCRIPTION

1.1: Perspective

1.2: Perspective

1.3: Front

1.4: Back

1.5: Left

1.6: Right

1.7: Top

1.8: Bottom

(Continued)

1.9: Use state

Reproduction 1.9 is a perspective view showing the claimed design in a state of use.

The broken lines immediately adjacent to the shaded areas depict the bounds of the claimed design, while all other broken lines are directed to environment. The broken lines form no part of the claimed design.
